UNITED STATES PATENT OFFICE.

LEANDER P. HAMILTON AND HEZEKIAH K. MOURNING, OF ALTAMONT,
KANSAS.

WINDOW-SHADE EXHIBITOR AND CABINET.

SPECIFICATION forming part of Letters Patent No. 623,543, dated April 25, 1899.

Application filed June 30, 1898. Serial No. 684,843. (No model.)

To all whom it may concern:

Be it known that we, LEANDER P. HAMILTON and HEZEKIAH K. MOURNING, citizens of the United States, residing at Altamont, in the 5 county of Labette and State of Kansas, have invented a new and useful Window-Shade Exhibitor and Cabinet, of which the following is a specification.

The invention relates to improvements in 10 window-shade exhibitors and cabinets.

The object of the present invention is to improve the construction of devices for exhibiting window-shades and to provide an inexpensive and efficient combined cabinet 15 and rack adapted to receive a large quantity of window-shades and capable of advantageously displaying samples of the same.

A further object of the invention is to protect the stock from dust and afford ready access to the same without interfering with the 20 samples displayed, and to arrange the latter so that they will indicate the character of goods in the various compartments.

The invention consists in the construction 25 and novel combination and arrangement of parts hereinafter fully described, illustrated in the accompanying drawings, and pointed out in the claims hereto appended.

In the drawings, Figure 1 is a perspective 30 view of a display-rack and cabinet constructed in accordance with this invention. Fig. 2 is a vertical longitudinal sectional view. Fig. 3 is a transverse sectional view. Fig. 4 is a horizontal sectional view. Fig. 5 is a 35 detail sectional view of one of the slides, illustrating the manner of mounting the same on the cabinet.

Like numerals of reference designate corresponding parts in all the figures of the 40 drawings.

1 designates a cabinet provided with suitable legs 2, preferably arranged at the front and back of the cabinet and provided with curved feet or bottom pieces; but any other 45 desired arrangement of legs may be employed. The cabinet, which is oblong in vertical and horizontal section, is provided with a central vertical longitudinal partition 3, and has a vertical series of horizontal shelves 50 4 at each side of the partition 3 to divide the

spaces between the partitions and the sides into compartments for the reception of window-shades. Each compartment is designed to be of sufficient size to accommodate one dozen shades.

55

The front end of the cabinet is provided with hinged doors 5, preferably provided with glass panels, as shown, and hinged at their inner edges to a vertical strip or piece arranged at the front end of the vertical partition 3; 60 but the doors may be hung in any other desired manner. The outer edges of the doors are provided with eyes 6, which are engaged by hooks 7 for holding the doors closed, and suitable handles are provided to facilitate 65 opening the doors. Instead of employing the hooks and eyes any other suitable form of locking device may be provided for holding the doors closed.

The window-shades 8, which are displayed, 70 are arranged in a horizontal position at the sides of the cabinet, as clearly illustrated in Figs. 1 and 4 of the accompanying drawings, and they are located adjacent to and in line with the compartments in order to indicate 75 the color and character of the window-shades contained in the various compartments, whereby the handling of the window-shades in trade is greatly facilitated. Each window-shade 8 is supported by brackets 9 and 10, 80 mounted, respectively, on a vertical strip 11 and a horizontal slide 12, and each side of the cabinet is provided with this construction. The vertical strip or bar 11 is arranged adjacent to the front of the cabinet, and the 85 brackets 9 carried by it are fixed. The slides 12, which are located near the back of the casing, are provided at their upper and lower edges with flanges 13, which engage upper and lower grooves or recesses of flanged 90 strips 14, which form ways for the slides and which are secured to the cabinet. As the window-shades vary in length it is necessary to arrange the supporting-brackets at various distances apart, and the slides which are capable of horizontal adjustment provide for this arrangement of the brackets. By adjusting a slide horizontally in the ways the distance between its bracket and the companion bracket on the vertical bar or strip 9 may 95 100

be varied and increased or diminished as desired.

The brackets 9 and 10 are of the ordinary construction, and the slides are secured at 5 the desired adjustment by screws 15, passing through them and engaging the cabinet. The window-shades are rolled up, as illustrated in Fig. 1 of the accompanying drawings; but any one of the window-shades may be readily 10 unrolled and displayed without interfering with the other shades.

The invention has the following advantages: The combined cabinet and rack, which is simple and comparatively inexpensive in 15 construction, is adapted to contain and protect from dust a large number of window-shades, and it is capable of displaying a large variety of shades advantageously and of arranging the samples to indicate the color and 20 character of goods contained within the various compartments. The slides upon which the rear brackets are mounted are capable of ready adjustment on window-shades of different lengths.

25 Changes in the form, proportion, and minor details of construction may be resorted to without departing from the spirit or sacrificing any of the advantages of this invention.

What we claim is—

30 1. A window-shade exhibitor and cabinet comprising a cabinet or casing provided with a vertical series of interior compartments for containing window-shades, a vertical series of fixed brackets sustained upon one side of 35 the cabinet upon the outside thereof in line with the respective compartments, and a second and corresponding number of brackets disposed upon the opposite side of the casing in line respectively with said first-mentioned 40 series and adjustably supported, the fixed

and adjustable brackets being adapted to receive and display window-shades, and whereby window-shades of different lengths can be supported by the manipulation of said adjustable brackets, substantially as described. 45

2. A window-shade exhibitor comprising a cabinet provided with a vertical series of interior compartments for containing shades, two independent series of brackets disposed upon the outside of the cabinet at opposite 50 sides thereof and in line with or opposite the respective compartments, whereby sample shades can be supported upon brackets opposite the compartments containing corresponding shades, and a vertical series of horizontally-adjustable slides mounted upon one side of the cabinet and adapted for supporting one of said series of brackets, whereby the latter can be independently adjusted toward and from the complementary brackets, substantially as described. 55

3. A window-shade exhibitor and cabinet comprising a cabinet provided with a series of interior compartments for containing window-shades, and two series of brackets disposed upon the outside of the cabinet at opposite sides thereof and in line with or opposite the respective compartments, whereby sample shades can be supported upon brackets opposite the compartments containing corresponding shades, substantially as described. 65

In testimony that we claim the foregoing as our own we have hereto affixed our signatures in the presence of two witnesses.

LEANDER P. HAMILTON.
HEZEKIAH K. MOURNING.
